UNITED STATES PATENT OFFICE

126,813

DESIGN FOR A COMBINED HOLDER AND PERFUME CONTAINER

Robert B. Karoff, New York, N. Y., assignor to Stuart Products Co., Inc., St. Paul, Minn.

Application March 2, 1940, Serial No. 90,631

Term of patent 3½ years

To all whom it may concern:

Be it known that I, Robert B. Karoff, a citizen of the United States of America and a resident of the city, county, and State of New York, have invented a new, original, and ornamental Design for a Combined Holder and Perfume Container, of which the following is a specification, reference being had to the accompanying drawing, forming a part thereof.

In the drawing:

I claim:

The ornamental design for a combined holder and perfume container, as shown.

R. B. KAROFF.
